US0D1004110S

(12) **United States Design Patent** (10) **Patent No.:** **US D1,004,110 S**
(45) **Date of Patent:** **** Nov. 7, 2023**

(54) **WAX MELTING MACHINE**

(71) **Applicant:** **GUANGDONG YORKMA INDUSTRIAL CO., LTD.**, Guangzhou (CN)

(72) **Inventor:** **Fengrong Zhang**, Guangzhou (CN)

(**) **Term:** **15 Years**

(21) **Appl. No.:** **29/816,496**

(22) **Filed:** **Nov. 23, 2021**

(51) **LOC (14) Cl.** **24-01**

(52) **U.S. Cl.**

USPC **D24/200**

(58) **Field of Classification Search**

CLAIM

The ornamental design for a wax melting machine, as shown and described.

DESCRIPTION

FIG. 1 is a perspective view of a wax melting machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

(Continued)

The broken lines in the drawings depict portions of the wax melting machine that form no part of the claimed design.

1 Claim, 8 Drawing Sheets
